LIQUID PUMP

Walter Eickele, Summit, N. J.

Application April 19, 1950, Serial No. 156,883

3 Claims. (Cl. 103—131)

1

This invention relates to improvements in liquid pumps. In particular, the invention is directed to pumps of a planetary piston type or style, in which a cylindrical impeller is caused to gyrate within a larger cylindrical pumping compartment to drive fluid therethrough by cyclic transposition of the clearance space between the impeller and the pumping compartment walls.

Planetary pumps as a class are simple and effective units, relatively inexpensive to construct and particularly useful for moderate pressures in pumping fluids which contain solids as could deleteriously interfere with mechanical components of gear or other types of pumps. The direction of frictional engagement between the impeller and the pumping compartment surface does not reverse, as in the case of a reciprocating pump, and hence solids are readily carried from intake to discharge. In order to maintain adequate sealing engagement of the impeller and the compartment walls under varying conditions of pressure and temperature, and also to resist destruction by entrained solids, the impellers are preferably constructed either in whole or in part of a yielding deformable material such as rubber or synthetic rubber.

Advanced technique in materials and in processes of molding synthetic rubber and other deformable plastics has made it possible to enlarge the field of application for planetary impeller pumps, particularly with regard to uses for high pressures. Thus, instead of using simple planetary pumps for moderate pressure work in the range up to 30 pounds per square inch, these pumps may now be specified for relatively higher pressures. Attendant with using the higher pressures is the requirement for impellers which will withstand the resulting increase in stresses and maintain pump efficiency.

The principal objective of the present invention is to provide an improved planetary piston pump.

A further object of my invention is to provide an impeller for planetary piston pumps which is capable of withstanding relatively high pumping pressures without objectionable strain.

A still further object of the invention is to provide a novel and improved construction for a planetary pump impeller comprising a rigid metallic core covered with a molded, deformable wear resistant material; the insert and the molded material covering being proportioned so as to present an efficient and effective combination for optimum manufacturing conditions and utility.

With the above objects in mind, as well as others which will become apparent during a consideration of the following detailed specification, the invention comprises the construction and

combination of parts as are hereinafter fully described, it being understood that the disclosure is merely illustrative of the principles of my invention and that obvious changes may be made in the details of construction and the arrangement of parts which are within the scope of the appended claims.

In the drawing:

Figure 1 is a cross-sectional elevation view of a planetary piston pump which incorporates features of my invention.

Figure 2 is a vertical cross section view taken through the pump of Figure 1 on line 2—2,

Figure 3 is a top plan view of an insert used in the construction of the impeller for the pump of Figures 1 and 2, with a diagrammatic outline of the molded covering therefor, and

Figure 4 is a vertical cross section view of the insert of Figure 3 taken on line 4—4.

Referring to the drawing, Figure 1, L creates a hollow housing 10 by mating and securing together a pair of metallic half housing sections 10' and 10", each half section being provided with a suitable anti-friction bushing 11 within which is journalled a rotatable pump shaft 12. A ring gasket 18 in grooves or channels outlining the mating half sections provides a liquid seal therebetween. The open space formed within the pump housing structure 10, see also Figure 2, includes a substantially cylindrical pumping compartment above which is an irregularly shaped open space for intake and discharge of liquid being pumped. The right hand end of shaft 12 terminates within a closed boss and the left hand end of the shaft projects out of the housing from an open boss to permit connection with a suitable source of power as an electric motor. A liquid seal is provided on the end of the shaft projecting from the housing including a deformable ring gasket 13 having an annular groove on the inner face thereof, the latter of which accommodates a coil compression spring 14 interposed between the gasket and bushing 11 to press against the gasket and bushing 11 to press against the gasket and deform it radially into liquid sealing engagement with the shaft and with the inner cylindrical surface of the open boss. Thrust washer 15 clearing shaft 12 forms an abutment for gasket 13 and is secured in place by the use of knurled cap nut 16 which threadedly engages the outside surface of the boss, and a lock nut 17 retains cap nut 16 in an adjusted position.

Shaft 12, within housing 20, is provided with two pairs of opposed flats 19 which engage two C-shaped metallic eccentrics 20 assembled thereover, the eccentrics in turn being engaged by the two cylindrical impellers 21 closely fitted thereover. Impellers 21 are nested securely against the inner end faces of the pumping compart-

ment in their respective half sections of the housing, as shown in Figure 1, and they are spaced from each other by the use of a disc-like divider element 22 fitted over shaft 12. Divider 22 includes a peripheral ring gasket 23 in sealing engagement with a grooved channel formed on the inner cylindrical surface of the pumping compartment at the joint of the mating housing sections and also includes a pair of flat fibre disc gaskets 24 for rotative sealing against shaft 12. Fibre gaskets 24, furthermore, provide wearing surfaces against which eccentrics 20 and impellers 21 may slide, and in this manner the pump is effectively sealed into two separate pumping compartments. At the same time, shaft 12 is confined by the assembly described against movement axially of the pumping compartment.

Impellers 21 are substantially cylindrical in external form, excepting at the top portions, where they are rectangularly grooved as at 25 to provide engagement with the metal divider plate 30 which is removably affixed to the inner surface of the pumping compartment, depending downwardly therefrom. During pumping, plate 30 serves to restrain the impellers against rotation while permitting gyration, and a sliding liquid seal is maintained in the slots 25 at the surfaces of contact with divider 30. Since divider 30 extends continuously between the ends of the pumping compartment, intake on the left side, Figure 2, is partitioned from discharge on the right side. Divider plate 30 also engages a closely fitted slot on the disc-like compartment divider 22 to avoid any tendency for that part to rotate during pumping.

To impart maximum rigidity to impeller 21 and yet retain the advantages of the deformable impeller materials, as hereinbefore considered, I construct the impeller with a substantially cylindrical hollow metallic core 26, Figures 3 and 4, completely shrouded with molded synthetic rubber 27 or the like. Light weight metal such as aluminum is preferably used for the core, the upper portion of which is grooved as at 25' to provide for the slot 25 in the external impeller configuration. Flanking groove 25' in the core 26 are ridges or protuberances 28 which project diametrically to the extent that they lie slightly under the outside diameter of the finished impeller, thus reinforcing the molded covering adjacent the slot. Ridges 28 are intersected transversely with a series of parallel concentric outside grooves 28', the latter of which run continuously of the external periphery of core 26 and provide for keying the molded covering therewith while permitting a limited degree of yielding of covering 27 with respect to the core.

The internal bore of core 26 is provided with grooves in the form of a square thread 28" interlocking with the molded rubber 27, the latter serving as a bearing in which eccentric 20 revolves. One reason for providing an internal thread 28" rather than separate grooves is the simplicity of manufacturing, another important object is to obtain a helical depression in the bearing surface in contact with the eccentric to act as a lubricating groove. This groove is formed in the molding process, the shrinkage of the rubber or synthetic compound between the threads being greater due to the greater depth of the material and smaller directly over the threads where the depth is smaller.

In order to provide further means for prevent-

ing separation of the outer covering portion from the core due to inertia forces during operation of the pump, I provide a plurality of evenly spaced radial holes 39 in core 26. The material in these holes serves to tie the outer and inner coverings together or to provide mechanical means for anchoring the outer covering to the core so that the impeller is capable of operating under higher pressures even if the adhesive bond between covering and core is imperfect or if there is no such bond at all. After the covering is molded to the core, a certain shrinkage takes place which continues for some time before the pump is used. This shrinkage serves to produce a considerable tension in the covering and in the tendons extending through holes 39, so that the covering adheres tightly to the core. Another function of holes 39 is to permit a limited flow of covering material from the inside portion of impeller 21 to the outside to prevent excessive pressure on the bearing surface in case of material swelling. While rubber or synthetic rubber may be considered incompressible, they nevertheless may be subject to swelling when in contact with certain substances, of which the pumping medium may be one. Near the ends of the bore in impeller 21 excessive pressure may be relieved through the layer of covering material on the lateral faces of the impeller. Accordingly, the radial holes 39 particularly serve to relieve excessive pressure in the central portion of the impeller. A certain flow of material is also required on the outside surface of impeller 21 whose outer periphery contacts the internal surface of housing 10. Due to the yieldability of the material a better seal between impeller and housing is obtained as the impeller diameter plus the stroke may be actually larger than the diameter of the internal bore of housing 10. In consequence, flow of material near the point of contact takes place in a peripheral direction, which is the reason for making grooves 28' or ridges 28 in core 26 parallel. While it is well known that an impeller of rubber-like resilient material has several advantages which permit less accuracy in the component parts, and also allow the passage of certain solids in the pumping medium without damage to the pump, I wish to point out particularly that with the proper metallic core as described the characteristics of the impeller can be greatly improved to permit greater speeds and higher working pressures. Also, I have found that by letting the synthetic rubber act as a bearing on eccentric 20 rather than metallic core 26, the life of such a bearing is greatly increased. Of importance, ridges 28 extend circumferentially of core 26 only for a short distance and limit the yieldability of molded covering 27 only within the port openings. In this manner a tight liquid seal is maintained while the impeller is in upper dead center, which is a particularly desirable condition for high pressure pumping, and at the same time the balance of the impeller surface may readily deform slightly to compensate for surface irregularities or for interference from solids entrained with the liquid being pumped. The sides of the impellers are chamfered or relieved as at 40, Figure 1, to eliminate the side friction at the inner portions of the impellers and to provide passages through which pumping fluid may pass from slots 25 to the bearings for lubrication. The flow of fluid occurs by virtue of the pumping action which takes place in slots 25, causing a surge back and forth

between the slots through chamfers 40 and between the bearing surfaces of the impellers and eccentrics 20.

During pump operation the impellers gyrate in the pumping compartment to carry the liquid which flows to the pump via nipple 37 from intake to discharge, whereon it is forced outwardly through nipple 38. While the angularity of impeller slot 25 with respect to divider plate 30 is continuously changing, the resulting interference is effectively absorbed in displacement of the covering 27 without adverse effect on the sliding liquid seal therebetween.

It will be understood that various changes may be made in details of the construction and operation of the pump of my invention as compared with the above description of a preferred embodiment thereof, which are within the scope of the subjoined claims.

While the preferred embodiment shows a pump having a pair of impellers to provide a balanced action, it is apparent that any other number of impellers or a single impeller could be used. Also, it should be understood that the term "rubber" or "synthetic rubber" is here intended to denote any resiliently deformable synthetic or rubber-like material.

I claim:

1. A cylindrical impeller for a pump as described comprising a hollow cylindrical metallic core having radial holes, spiral threads in the inner periphery of said core, spaced circumferential peripheral grooves in the outer surface of said core and having their axis on the axis of the core, and a covering of rubberlike material surrounding said core on the inside, on the sides, and on the outer surface, said rubberlike material extending through said radial holes to anchor the outer portion of said covering to the inner portion of said covering, the grip of 40 said covering around said core being substantially increased due to shrinkage of said rubber-

like material after the molding process, said inner portion of said covering providing a bearing for a revolving driving member of said pump, said radial holes having their outer ends terminating in the bottoms of the circumferential peripheral grooves.

2. A cylindrical impeller for a pump as described comprising a hollow cylindrical metallic core having a plurality of radial holes, a plurality of circumferential grooves in the outer periphery of the core, a spiral continuous groove in the inner periphery of the core, a covering of rubberlike material under tension tightly surrounding said core on the inside, on the sides, and on the outside, said rubberized material entirely filling all of said grooves, and tendons of said rubberlike material under tension extending through said radial holes to tie the inner and outer portions of said covering together, the tension of said rubberlike material being produced by shrinkage after the molding process.

3. The construction as claimed in claim 2, the sides of said impeller having relieved portions to reduce friction and to aid lubrication.
